By *Alfred J. Randolph Jr.* Attorney

UNITED STATES PATENT OFFICE.

HOWARD GRAHAM, OF NEW BRAUNFELS, TEXAS.

TRUSS.

Application filed November 17, 1923. Serial No. 675,346.

To all whom it may concern:

Be it known that I, HOWARD GRAHAM, a citizen of the United States, residing at New Braunfels, in the county of Comal and State 5 of Texas, have invented certain new and useful Improvements in a Truss; and I do hereby declare the following to be a full, clear, and exact description of the invention, such as will enable others skilled in 10 the art to which it appertains to make and use the same.

The invention relates to new and useful improvements in rupture trusses or supporters and has for its object to provide a truss 15 or supporter which when worn, will exert the desired or proper pressure at the proper point or points and which will give comfort to the wearer and yield and conform to every movement of the body.

Another object of the invention is to provide a device of the character stated, in which there is employed a number of fingers or pads, each of which exerts the same pressure, as in the case of the fingers of a human 25 hand.

Other objects and advantages will be apparent from a consideration of the following description taken in connection with the accompanying drawings, in which:—

Figure 1 is a perspective view of a truss embodying my invention;

Figure 2 is a detail view showing the arrangement of the pads or fingers;

Figure 3 is a sectional view through a 30 pad and the belt, showing the pad attached to the belt;

Figure 4 is a perspective view showing the rear side of the intermediate pad, and showing the means for securing the same to 35 the belt, and

Figure 5 is a view similar to Figure 4 but showing one of the end pads.

Referring in detail to the accompanying drawing, the numeral 1 indicates generally, 40 a belt, preferably constructed from elastic material and having its ends detachably and adjustably connected by means of small straps 2 and by small buckles 3. A portion of the inner side of the belt is covered or 45 reinforced by a strip of leather or like material as shown at 4. The belt 1 and the reinforcing strip 4 are each provided with sets of openings arranged in pairs one above the other, as shown at 5, the perforations in

the belt registering with respective perforations in the reinforcing strip. 55

Each of the pads 6 comprises a front cushion portion 7 and a semi-rigid backing 8. The cushion portion covering is of soft flexible material, and covers the padding or filling 9 composed of particles of cork, rubber or the like. Secured to the back of each of the pads 6, is a securing means 10. The securing means shown in Figure 4, for securing the intermediate pad to the belt, 60 comprises a single length of wire coiled and doubled upon itself intermediate its ends as at 11, and having its arms extend in the same general direction and each provided with a pair of loops 12. The end pad shown in Figure 5, has its securing means attached thereto as by stitching, as in the case of the securing means for the intermediate pad, and the securing means 10 for the end pads 65 comprises a single length of wire bent to provide a base or attaching portion and doubled upon itself to form a pair of spaced coils 13. 70

The attaching portion 10 of the intermediate pad, has its coils 12 passed through the intermediate pairs of perforations in the belt and reinforcing strip, and the end pads have the loops 13 of their attaching portions 10 pass through the vertically spaced end pairs of perforations in the belt and reinforcement 4. After the loops 12 and 13 have been passed through the pairs of openings 5, a narrow strip of leather or other suitable material is passed through the upper set of coils or eyes, and a second strip passed 75 through the lower coils or eyes, these strips being indicated at 14. If found desirable, shims 15 may be interposed between the backing 8 of the pads and the portions 4, in order that the coils or eyes 12 and 13 will 80 tightly engage the securing strips 14 to prevent their becoming lost or displaced and thus permitting the pads to move out of their proper relative positions. 85

Slidably mounted upon the belt 1, is a 90 loop 16 to which is swingingly connected a buckle 17. A crotch strap 18 is secured at one end to the loop 16 by the buckle 17. The end of the crotch strap 18 remote from the end secured to the buckle, is provided with a plurality of fingers 19, one finger being provided for each of the pads 6, and the fingers are permanently attached to the belt 100 105

1 as by means of the stitches which secure
the reinforcing strip 4 in place. As shown,
the fingers 19 are secured to the belt at a
point in rear of the pads, and extend down-
wardly below the lower ends of the pads.

While I have shown and described the
preferred embodiment of my invention, it is
to be understood changes in the construc-
tion, combination and arrangement of parts
10 may be made provided they fall within the
scope of the appended claim.

Having thus described the invention, what
I claim is:

In a device of the class described, a sup-

porting band, a plurality of relatively nar-
row closely arranged pads carried by said
band, said pads being adapted to simulate
the action of the fingers of the human hand,
each pad having a resilient wire fastened
thereto, said wire having portions arranged
15 at a right angle to its general plane and
formed into an upper and a lower eyelet,
said supporting band having slots through
which said eyelets are passed in an outward
direction, and strips removably extending 20
through the eyelets outwardly of the band.

In testimony whereof I affix my signature.
HOWARD GRAHAM.
